UNITED STATES PATENT OFFICE.

DAVID H. FINDLAY, OF PASADENA, CALIFORNIA.

GOLF PUTTER AND METHOD OF FORMING THE SAME.

Application filed September 22, 1926. Serial No. 137,043.

This invention relates to improvements in golf clubs and particularly to golf club heads and to the method of making the same. The invention concerns primarily a golf putter 5 although it may be applied to several other golf clubs commonly referred to as the irons, such as the midiron, mashie and similar clubs.

An object of this invention is to provide a 10 golf club head such as a head for a putter, which is formed of two metals, one being relatively hard and forming the outside shell and the other being relatively soft and heavy filling a cavity in the shell to give the head 15 proper balance and proper weight.

Another object of this invention is to provide an improved method for constructing a golf club head having the above mentioned characteristics.

20 With the foregoing and other objects in view which will be made manifest in the following detailed description and specifically pointed out in the appended claims, reference is had to the accompanying drawings 25 for an illustrative embodiment of the invention, wherein:

Figure 1 is a perspective view of a putter head embodying the invention,

Fig. 2 is a vertical section taken substantially on the line 2—2 of Fig. 1, and

Fig. 3 is a vertical section taken substantially on the line 3—3 of Fig. 2.

Referring to the accompanying drawings wherein similar reference characters designate similar parts throughout, the general exterior shape of the club may be varied under various circumstances, but in all cases it has the general shape of the conventional golf club head. The improved head consists 35 of an outside shell 10 preferably formed of a relatively hard metal. This metal in the preferred form of construction is aluminum or an aluminum alloy, although it may be changed using brass, bronze, copper, mild 40 steel or any equivalent substance. Inside of the shell there is cored out a longitudinal cavity 11, one end of which is open at the outer or free end of the head. In forming this cavity in the shell, a plurality of small 45 projections 12 are preferably formed on the interior of the shell. The cavity 11 is then filled with a relatively heavy metal 13 which in the preferred form of construction is white metal, although this may be lead or 50 any alloy of lead or any equivalent metal which will give the desired weight. This

heavy metal fully occupies the cavity 11 and extends from the open end or the free end of the head to the base of the neck 14 which receives the shaft. 60

In constructing the improved head, the shell is first cast, a core being employed to form the cavity 11 and the opening through the neck 14. This core is so formed that when the shell is cast, the projections 12 will 65 be formed thereon. After the shell is cast, it is heated to a temperature very nearly as high as the melting point of the metal forming the shell. While under this temperature the heavy metal 13 is poured into the 70 cavity and the complete club head allowed to cool. In constructing the club head it is quite important that the club head be made in the above mentioned manner for the reason that the shrinkage of both metals during 75 cooling will be approximately the same and the heavy metal 13 will be tightly held within the shell 10. If the heavy metal 13 is poured into the shell while the shell is cool, on cooling the heavy metal will tend to 80 shrink and pull away from the interior surface of the shell, so that the heavy metal will be loose within the shell. When the heavy metal and the shell are both heated and cooled together, the heavy metal will remain 85 tight within the shell. The projections 12 serve to keep the heavy metal from falling out of the cavity. When so much of the head is completed, the opening in the neck 14 is reamed out and the shaft is inserted 90 into it.

It will be found that a club constructed in the above described manner has a very nice balance and has the desired amount of weight in the head without making a large 95 sized head. The relatively hard outer shell serves as a good protective medium which cannot be easily deformed or bent out of shape. If the soft metal were exposed, on the surface of the club on placing the club 100 in a bag with other clubs, the other clubs would be very apt to scar the soft metal and deform it. In this way the relatively hard outer shell protects the soft metal. It will also be found that in using the improved 105 club on striking the ball there is a pleasing click as distinguished from the dull thud which occurs in using clubs of prior constructions.

From the above described construction 110 it will be appreciated that a novel golf club is provided having a relatively hard

outer shell enclosing a relatively soft heavy metal, thus giving the desired weight to the head without causing the head to be of an unusually large size.

5 It will be understood that various changes may be made in the detail of construction without departing from the spirit and scope of the invention as defined by the appended claims.

10 I claim:

1. The method of making a golf club head which consists in casting a shell having a neck portion extending therefrom, allowing the same to cool, heating the same to a temperature just below the melting point of the metal forming the shell, pouring heavy metal into the shell through the neck to said body

portion, and allowing the shell and heavy metal to cool.

2. A golf club head comprising a substantially angular tubular shaped member which has a cavity extending therethrough one end of said tubular shaped member providing a reduced neck portion, and the other end of said tubular shaped member providing a body portion, there being aligned projections on the interior of said cavity throughout said body portion, and a filling of lead in said body portion, said filling being held in place by said projection. 30

In testimony whereof I have signed my name to this specification.

DAVID H. FINDLAY.
